VAPORIZER

Filed March 20, 1930

LUTHER W. SHIPMAN,
INVENTOR.

BY *Harold Shipman*
ATTORNEY

UNITED STATES PATENT OFFICE

LUTHER WELLINGTON SHIPMAN, OF ALMONTE, ONTARIO, CANADA

VAPORIZER

Application filed March 20, 1930. Serial No. 437,520.

This invention relates to a vaporizer and has for its principal object the provision of a vaporizing chamber in which pharmaceutical preparations or the like can be subjected to heat and a means whereby a circulation of air through the chamber may be obtained whereby the fumes from the heated pharmaceutical or other preparations may be emitted at a pre-determined place.

19 A further object of my invention is to provide a supporting structure for the chamber, which will normally retain the same above a heating medium but which will permit the chamber to be swung around so as to facilitate access to the heating medium.

20 A further object is to provide supporting members in connection with a vaporizing chamber, which supporting members are supported on a supporting frame in which a heating medium is retained or the chamber, with its associate supporting members, may be placed upon the upper end of a lamp chimney or on the flat surface of a stove or any other similar heating medium.

23 With the foregoing and other objects in view as will appear as the description proceeds, the invention consists of the novel construction, combination and arrangement of co-operating elements as hereinafter more 23 specifically set forth, claimed and shown in the accompanying drawings forming a part of the present application in which:

Fig. 1 is an elevation view of the preferred embodiment of my invention.

35 Fig. 2 illustrates the chamber, showing how it may be conveniently supported on the upper end of a lamp chimney.

Fig. 3 is a section view of a lamp chimney showing one of the tension rods in position to retain the vaporizing chamber in position.

Like numerals of reference designate corresponding parts throughout the different views.

3 indicates an oil lamp, the bowl of which 45 is in the base 4 and extends up through a central opening in the cover 5. The base 4 may, if desired, be weighted in any desired manner.

6, 7 and 8 are upright members, preferably rods, which are suitably welded or otherwise attached in spaced relationship to the base 4.

Each of the uprights are provided with a socket 9, 10 and 11 respectively at their upper ends, the purpose of which will be herein-after mentioned. 12 is a brace, preferably of annular formation, supporting the upper ends 55 of the upright members 6, 7 and 8 in proper spaced relationship.

14 is a vaporizing chamber having a lid 15 through which the ends of the nipples 16 and 17 extend and are supported in any desired 60 air-tight manner. This chamber is for holding any pharmaceutical or other preparation which is to be vaporized. Attached in any desired manner to the bottom of the chamber 14, I provide legs 18, 19 and 20. Preferably, these legs are made from wire having a downwardly projecting shank portion and an inwardly extended portion which is looped back under itself. The downwardly projecting portions of the legs are designed to fit into 70 their respective sockets 9, 10 and 11, the legs being in corresponding spaced relationship to the uprights 6, 7 and 8. The downwardly projecting portion of the leg 18 with the socket 9 will provide a pivotal connection in which 75 the container 14 may be pivoted to the position as shown in dotted lines Fig. 1, when it is desired to facilitate access to the lamp 3. The downwardly formed slots in the sides of the sockets 10 and 11 are so formed as to permit 80 the downwardly projecting portions of the legs 19 and 20 respectively to be swung into snap engagement with the sockets 10 and 11.

The nipple 17 has one end of the tube 21 85 connected to its outer end, the other end of the tube being provided with an air compression bulb 22, which when pressed will force air into the chamber 14. 23 is a tube of convenient length, one end of which is attached 90 in communication with the nipple 16, while the other end may be provided with any removable nozzle 24. The chamber 14 and the base 4 may be provided with any desired means for facilitating the raising of their 95 respective covers 15 and 5.

With the legs formed and attached to the chamber 14 in the manner as hereinbefore described, the chamber may be positioned on the upper end of a lamp chimney as shown in 100

- 5 Fig. 2. The portions of the leg which extend inwardly and are turned back under themselves provide a spacing medium between the bottom of the chamber and the upper marginal edge of the lamp chimney on which these portions will rest. The chamber 14 may be placed on the flat surface of a stove top or any other similar heating means and the downwardly projecting portions of the legs 10 18, 19 and 20 will support the same in spaced relationship to such flat top so that the same will be moderately heated. If desired tension rods 26, having coiled portions 27 intermediate their hooked ends, may be connected at 15 one end to the respective legs 18, 19 and 20 and the lamp burner 28.

In the use of the vaporizer as hereinbefore described it will be found most efficient to use a complete structure as illustrated in Fig. 20 1. The nozzle 24 may be held close to or inserted into a person's nostrils or mouth and the compression bulb 22 operated to force a circulation of air through the chamber 14 and discharge from the nozzle 25 such air with the fumes of the pharmaceutical or other preparation which is being vaporized from the chamber 14. If desired, the tubes 21 and 23 may both be removed or the cover, with its 25 associated attachments, may be removed and the fumes allowed to circulate freely in the room. If desired, the tube 23 may be used and the fumes inhaled without the necessity of forced circulation by the compression bulb 22.

28 In the disclosure as shown in the annexed drawings and as hereinbefore described, I have shown an oil lamp 3 as a heating medium but I do not wish to be thus limited as various other heating mediums may be employed 30 with equal adaptability to give as efficient results and could be retained in combination with the frame 6—7—8—12 in proper spaced relationship from the chamber 14 with due consideration being given to the heating 35 strength of the heating medium used.

The foregoing specification and annexed drawings disclose the preferred embodiment of my invention, but it is to be understood that minor changes may be resorted to in the 40 commercial adaptation of my invention without departing from the scope of the invention as hereinafter claimed.

What I claim as new is:

45 A vaporizer comprising a vaporizing chamber; supporting legs carried in spaced relationship by the bottom of said chamber; a supporting base; a heating medium carried by said base; a frame, supported relative to said base in which one of said legs is swivelly supported and the remaining said legs removably and resiliently retained in said frame.

In testimony whereof, I affix my signature
LUTHER WELLINGTON SHIPMAN.
